(57) **CLAIM**

The ornamental design for an electric connector, as shown and described.

DESCRIPTION

FIG. 1 is a top plan view of an electric connector of an embodiment showing my new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a rear, top, and left side perspective view thereof in use condition; and,

FIG. 7 is a rear, bottom, and left side perspective view thereof in use condition.

The broken line in the figure drawing views is included for the purpose of illustrating environment and forms no part of the claimed design.
